UNITED STATES PATENT OFFICE.

REGINALD TROY TAYLOR, OF NEW VIRGINIA, IOWA.

COIN CONTAINER.

Application filed July 12, 1922. Serial No. 574,495.

To all whom it may concern:

Be it known that I, REGINALD TROY TAYLOR, a citizen of the United States, residing at New Virginia, in the county of Warren 5 and State of Iowa, have invented certain new and useful Improvements in a Coin Container, of which the following is a specification.

This invention relates to a coin container 10 and has for its principal object to provide a simple and cheaply constructed device which may be conveniently attached and may be conveniently secured within mail boxes or the like, and which is particularly 15 adapted for use in connection with rural delivery mail boxes, where it is desirable to place money in the box for stamps, money orders and other articles, and will make the same accessible to the mail carrier.

20 Another object of the invention is to provide a coin container of the above mentioned character, which will permit a mail carrier to take the coin or other articles placed in the container without the necessity 25 of removing his gloves to do so.

A still further object of the invention is to provide a coin receptacle of the class described, in which the delivery of the coin 30 may be accomplished by one hand, thereby permitting the mail carrier to have free use 35 of the other hand.

Another object of the invention is to provide a receptacle of the above mentioned character, which is inexpensive in its manufacture, simple in its construction, strong 40 and durable.

Other objects and advantages of this invention will become apparent during the course of the following description.

45 In the drawings forming a part of this specification and in which like numerals designate like parts throughout the same.

Figure 1 is a vertical sectional view taken through the front end of the mail box showing the coin receptacle mounted therein in 50 front elevation,

Figure 2 is a top plan view of the mail box with the cover swung open showing the coin receptacle mounted within the mail box,

55 Figure 3 is a transverse section of the mail box showing the coin receptacle in side elevation,

Figure 4 is a view showing the coin receptacle in perspective and mounted within 60 a section of the bracket, and

Figure 5 is a modification of the coin receptacle and bracket.

In the drawings, wherein for the purpose of illustration is shown the preferred embodiment of my invention, the numeral 1 designates the body of the well known type of mail box and is provided with the usual hinged cover 1'. A substantially U-shaped bracket 2 is secured to a side of the mail box and is located near the top thereof and adjacent the hinged cover as more clearly shown in Figure 1 of the drawings. The bracket 2 is provided with openings 3 for the purpose hereinafter to be fully described and is also fastened to the body of the mail box by any suitable means 2'.

A coin receptacle 4 which may be molded or formed of any suitable metal, is preferably scoop shaped and has its front portion open. Extending upwardly from the base 75 of the coin receptacle 4 are the sides 5, and these sides 5 increase in height from the open end of the coin receptacle 4 to the back portion 6 thereof, where the ends of the side members are bent back and held 80 together by means of the extensions 7 formed on one of the bent back portions of the side members to normally maintain the coin receptacle in its desired position. Pintle members 8 and 9 are provided on the side members 5 near the open end of the coin receptacle 4 and extend in opposite directions and are further adapted to be held in the openings 3 of the bracket 2 to pivotally support the coin receptacle 4 within the bracket 2. 85 To further aid in supporting the tray upon the bracket 2 and prevent the same from tilting backward are oppositely disposed arms 10 and 11 which are formed on the sides of the coin receptacle 4 near the back 90 end thereof. The open end of the coin receptacle 4 is provided with an elongated strip 12 which depends therefrom to provide a trip element.

In use, the coin receptacle is normally carried by the bracket 2 within the mail box 1 is shown in Figure 1 of the drawings. Upon a person coming to the mail box and desiring to post their letters and not having the necessary stamps to place thereon, he merely 100 deposits the necessary amount to cover the postage within the coin receptacle 4. He then places his letter in the mail box, and when the mail carrier comes to the mail box 105 to make the usual collections, he first places 110

his hand within the passageway of the mail box by lifting the cover and by engaging the trip member 12 with the palm of his hand, he causes the coin receptacle 4 to tilt 5 forwardly whereby the coins which are contained in the coin receptacle will be caused to be dropped into the hand of the mail carrier. In the mean time he can use his other hand for the purpose of taking the letter 10 which has been placed in the box and deposit it therein for collection. After he has removed the coins from the tray the container will resume its normal position in the bracket 2 as shown in Figure 3 of the drawings.

Ordinarily it is customary for rural mail boxes to be provided with a receptacle of a structure wherein the receptacle is stationarily mounted within the mail box, and it 20 is necessary for the mail carrier to first remove his glove and spend considerable time in taking the coins from within the receptacle whereby in my device it is not necessary for the mail carrier to waste considerable 25 time in taking off his glove and placing his hand down within the receptacle in order to obtain the coins placed therein. As the coin receptacle has its pintles formed near the open end of the same, it will be seen 30 that the coin receptacle will normally be in a position as shown in the drawings in Figure 3 whereby the open end of the receptacle is in a horizontal position, and furthermore the arms 10 and 11 aid in supporting 35 the coin receptacle 4 normally in a horizontal position. The back of the tray will thereby act as an aid for preventing the coins from accidentally falling out of the coin receptacle when the same are placed 40 therein.

In the modification as shown in Figure 5 of the drawings, a coin receptacle 4' has its sides 5' provided with oppositely extending pintles 8' and 9' for supporting the coin receptacle within the bracket 14. The back 45 portion 6' of the coin receptacle 4' has an angularly extending lip 7' which is adapted to rest within the cutter portion 14' formed in the back side of the bracket 14. The open end of the coin receptacle 4' is provided with an elongated strip 12' which depends therefrom to provide a trip element. 50

It is to be understood that the form of my invention as clearly shown and described is to be taken as the preferred example of the same and that various changes in the shape, size and arrangement of parts may be resorted to without departing from the spirit of the invention or the scope of the subjoined claim.

Having thus fully described my invention what I claim as new and desire to secure by Letters Patent, is:

A coin receptacle of the class described, comprising a bracket, a coin receptacle provided with oppositely extending pintles, said pintles extending from the sides of said coin receptacle to pivotally support the same in the bracket, arms formed on the top edge of the coin receptacle and adapted to rest on the bracket, and a trip member at its forward end for the purpose of tilting the coin receptacle.

In testimony whereof I affix my signature in presence of two witnesses.

REGINALD TROY TAYLOR.
